UNITED STATES PATENT OFFICE.

ADOLPH SCHNEIDER, OF CHICAGO, ILLINOIS, ASSIGNOR TO BANNING & BANNING, OF CHICAGO, ILLINOIS, A FIRM COMPOSED OF THOMAS A. BANNING, SAMUEL W. BANNING, AND WALTER BANNING.

COUNTER-PRESSURE REGULATOR.

1,086,862.

Specification of Letters Patent.

Patented Feb. 10, 1914.

Application filed May 16, 1911, Serial No. 627,420. Renewed June 2, 1913. Serial No. 771,341.

To all whom it may concern:

Be it known that I, ADOLPH SCHNEIDER, a citizen of the United States, residing at Chicago, in the county of Cook and State of Illinois, have invented certain new and useful Improvements in Counter-Pressure Regulators, of which the following is a specification.

The present invention relates to a counter-pressure regulator which operates to maintain a proportionate degree of pressure between two chambers, and is especially adaptable for use in conjunction with bottle-filling machines, where it is desired to maintain a differential degree of pressure within an air chamber and a liquid chamber, although, of course, the device is not necessarily limited for use with this particular mechanism, or necessarily in conjunction with an air and liquid chamber.

The principal objects of the present invention are, to provide a mechanism which is under all conditions and at all times automatic in its operation, which is compact in form and arrangement, and which is simple of operation and cheap of manufacture.

A further object of the invention is to provide a series of yielding surfaces which form a part of the regulator mechanism and which are effected by changes in pressure, and to so arrange these surfaces that they may be interchanged or others substituted for them, whereby any ratio or square area between said surfaces may be obtained, and hence any differential pressure between the pressure chambers can be had.

The invention further consists in the features of construction and the combination of parts hereinafter described and claimed.

In the drawings, Figure 1 is a sectional view of the regulator of the present invention; and Fig. 2 is a section taken on line 2-2 of Fig. 1.

As heretofore stated, this mechanism is especially applicable for use with bottle-filling machinery. In the art of bottle-filling, it is necessary, during the filling operation, to place the liquid under a pressure which will be of an amount to insure the proper flow of the liquid into the bottle. This is for the purpose of preventing the liquid from foaming during the filling operation. This operation is well known in the art of bottle-filling machines and need

not be discussed in detail in the present invention.

The apparatus of the present invention consists of a casing 3, as shown, cylindrical in cross section, closed at its upper end by a cap 4 and at its lower end by a cap 5. Entered into the cap 5 in the construction shown is a pipe 6 leading from a chamber containing liquid under pressure, or other pressure chamber. Entering into the casing is a conduit 7 leading from a second pressure chamber. In bottling apparatus this second pressure chamber is the air tank; and a third conduit 8 is provided, which leads from a source of pressure supply. The conduit 8 enters into the casing at the point where a bridge member 9 joins the interior walls of said casing. This bridge member, as shown in Fig. 1, extends from side to side of the casing in one direction, and, as shown in Fig. 2, lies free from the sides of the casing in the other direction. It is in the nature of a web or bridge, and is not a partition in the sense that it divides the casing at this point into two separate chambers. This bridge member is provided with a passageway 10 and a passageway 11. The passageway 10, as shown in Fig. 1, is in communication with the conduit 8 and opens to the upper side of the bridge 9; and the conduit 11 is in communication with an exhaust passage 12 at one end, and at its other end opens to the under side of the bridge member 9. It will, of course, be understood that the terms "upper" and "lower" as used in this connection merely apply in case the mechanism is positioned as shown in the drawings, and are not terms of limitation in any other sense.

Surrounding the bridge member 11 is a slotted strap-like member 13, comprising a body portion 14 and a cap piece 15. The cap piece has secured therein a screw-threaded tapered member 16, the end of which, as shown in Fig. 1, is adapted to seat within the open end of the passage 10; and the body of the strap-like member is provided with a tapered plug 17, the end of which is adapted to seat within the open end of the passage 11. By making one plug screw-threaded and adjustable, a greater or less degree of movement can be allowed the strap-like member, as will be apparent from a study of the drawing.

Positioned below the bridge member 9 is an upper partition wall 18 and a lower partition wall 19, both, as shown, in the form of a diaphragm member. These partitions 5 divide the interior of the casing into an upper chamber 20, into which air from the conduit 7 passes, and a lower chamber 21, into which air from the conduit 6 passes. Both of these diaphragms, as shown, are 10 joined to the body portion of the strap-like member 13, and each of the diaphragms, as shown, is secured in position by independent screw-threaded clamping rings, this construction enabling the diaphragms to be re- 15 moved and others substituted therefor without disturbing the general arrangement of the equalizing mechanism.

The body portion of the member 13 terminates in a stem 22, around which is placed 20 a collar 23 bearing against the diaphragm 18; and an interiorly screw-threaded collar 24 is placed on the lower end of the stem to retain in position the diaphragm 19. The diaphragm 19 is acted upon solely by the 25 pressure within the chamber 21, and the diaphragm 18 is acted upon solely by the pressure within the chamber 20. As shown, the diaphragm 18 is of larger area than the diaphragm 19, and hence will be actuated 30 by a less pressure than the diaphragm 18. This will result in a differential pressure being established within the chambers when the diaphragms are in equalized condition, that is, when the pressure on one is equal 35 to the pressure on the other, whereby the strap-like member is maintained in neutral position. For purposes of illustration, I might say that five pounds of pressure acting upon the diaphragm 19 will exert a cer- 40 tain pressure upon said diaphragm, and that a six pound pressure acting upon the diaphragm 18 will exert the same pressure upon this diaphragm. The pressure on the diaphragms will then be equalized and 45 movement of the strap-like member prevented. Thus, a differential pressure is maintained within the respective chambers, since the pressure per square inch in the chamber 21 exceeds the pressure per square 50 inch in the chamber 20.

In case it is deemed desirable to change the differential pressure existing between the chambers, this can be readily accomplished by the substitution of diaphragms 55 of different sizes from those illustrated, the size and arrangement of the diaphragms being dependent upon the difference in pressure which it is desired to obtain, and the variance in square area between the dia- 60 phragms depending upon the difference in pound pressure between the chambers desired.

The operation is as follows: Pressure is admitted through the conduit 8 from the 65 source of pressure supply until sufficient

pressure is accumulated within the chamber 20 to counteract the force of the pressure within the chamber 21 acting upon the dia- 70 phragm 19. When this is accomplished, the parts will be in the position shown in Fig. 1, and there will be a steady passage of air from the conduit 8 into the chamber 20 and a passage of air from the chamber 20 through the outlet conduit 12, maintaining a fixed degree of pressure within said chamber. The inletting of pressure and the ex- 75 hausting of pressure under these circum- 80 stances will not be very great, that is, the opening around the valves is somewhat ex- 85aggerated in the drawing from what it would be in actual use. If a pressure should accumulate in the chamber 21 in ex- 90 cess of the amount desired, it will force the diaphragm 19 upward, causing the tapered plug 17 to seat within the open end of the 95 passage 11, and thus cut off the exhausting of pressure from the chamber 20; and since both the plugs 16 and 17 are carried by the strap-like member, an upward movement of the plug 16 will take place simultaneously with the upward movement of the plug 17. This upward movement of the plug 16 will 100 open the passage 10 and admit pressure from the conduit 8 into the chamber 20. Such admittance will continue until the pressure within the chamber 20 is sufficient to lower the diaphragm 18 and the strap- 105 like member 13 and reverse the position of the valves with respect to the bridge 9, or bring them to the equalized condition here- 110 tofore referred to.

If an excess pressure should occur within the chamber 20, it will act upon the dia- 115 phragm 18 to lower it, thus lowering the strap-like member 13, unseating the tapered plug 17, and seating the plug 16, thus cutting off the flow of pressure into the chamber 20 and exhausting the pressure from said chamber. And this operation will continue until the proper equalization of pressure between the chambers 20 and 21 is brought about.

From the foregoing description, it will be observed that the equalizer of the pres- 120 ent invention is at all times automatic in its operation and does not depend upon the 115 actuations of the valve, levers, or other contrivances.

I claim:

1. In a counter-pressure regulator, the combination of a casing, a series of yield- 125 able partitions within said casing dividing the interior into separate chambers, means for admitting a medium under pressure to each of said chambers whereby each parti- 130 tion is operated by a pressure from a differ- ent source, means for exhausting pressure from one of said chambers, and a valve ac- tuated by the movements of said partitions to control the inlet and outlet of pressure

- from one of said chambers, substantially as described.
2. In a counter-pressure regulator, the combination of a casing, a series of diaphragms of different area within said casing dividing the interior thereof into separate chambers, means for admitting pressure to said chambers, means for exhausting pressure from one of said chambers, and valves actuated by the movements of said diaphragms to control the inlet and outlet of pressure from one of said chambers, substantially as described.
3. In a counter-pressure regulator, the combination of a casing, a bridge within said casing, said bridge having a pressure inlet passage and a pressure outlet passage therethrough, a movable partition within said casing dividing the interior into separate chambers, said bridge lying wholly within one of said chambers, means for admitting pressure to the other of said chambers, and a series of valves actuated by the movement of said partition to control the passage of pressure through the passages in said bridge, substantially as described.
4. In a counter-pressure regulator, the combination of a casing, a bridge within said casing, said bridge having a pressure inlet passage and a pressure outlet passage therethrough, a series of diaphragms within said casing dividing the interior thereof into separate chambers, said bridge lying wholly within one of said chambers, means for admitting pressure to the other of said chambers, and a series of valves actuated by the movements of said diaphragms to control the passage of pressure through said passages in said bridge, substantially as described.
5. In a counter-pressure regulator, the combination of a casing, a series of chambers within said casing, a bridge within said casing, said bridge having a pressure inlet passage and a pressure outlet passage therethrough, said bridge lying wholly within one of said chambers, means for admitting pressure to the other of said chambers, and means actuated by a difference in degree of pressure within said chambers for controlling said inlet and outlet passages in said bridge, substantially as described.
6. In a counter-pressure regulator, the combination of a casing, a series of chambers within said casing, a bridge within said casing having a pressure inlet passage and a pressure outlet passage therein, said bridge lying wholly within one chamber, means for admitting pressure to the other
- of said chambers, a strap-like member surrounding said bridge, valves carried by said strap-like member for controlling said inlet and outlet passages in said bridge, and means actuated by a differential pressure within said chambers for shifting said strap-like member and moving said valves, substantially as described.
7. In a counter-pressure regulator, the combination of a casing, a series of chambers within said casing, a bridge within said casing having a pressure inlet passage and a pressure outlet passage therein, said bridge lying wholly within one of said chambers, means for admitting pressure to the other of said chambers, a strap-like member surrounding said bridge, valves carried by said strap-like member for controlling said inlet and said outlet passages in said bridge, and means actuated by a differential pressure within said chamber for shifting said strap-like member, substantially as described.
8. In a counter-pressure regulator, the combination of a casing, a series of chambers within said casing, a bridge within said casing having a pressure inlet passage and a pressure outlet passage therein, said bridge lying wholly within one of said chambers, means for admitting pressure to the other of said chambers, a strap-like member surrounding said bridge, valves carried by said strap-like member for controlling said inlet and said outlet passages in said bridge, a series of diaphragms within said casing, each chamber having therein one of said diaphragms, and a connection between the diaphragms and strap-like member, substantially as described.
9. In a counter-pressure regulator, the combination of a casing, a series of chambers within said casing, a bridge within said casing having a fluid outlet passage and a fluid inlet passage therein, said bridge lying wholly within one of said chambers, means for admitting pressure to the other of said chambers, a member extending upon opposite sides of said bridge, valves carried by said member, said member being moved by a differential pressure in said chambers to shift said valves and controlling the flow of pressure through the inlet and outlet passages in said bridge, substantially as described.

ADOLPH SCHNEIDER.

Correction in Letters Patent No. 1,086,862.

It is hereby certified that in Letters Patent No. 1,086,862, granted February 10, 1914, upon the application of Adolph Schneider, of Chicago, Illinois, for an improvement in "Counter-Pressure Regulators," an error appears requiring correction as follows: In the assignment, name of the last-mentioned member of the firm, for "Walter Banning" read *Walker Banning*; and that the said Letters Patent should be read with this correction therein that the same may conform to the record of the case in the Patent Office.

Signed and sealed this 10th day of March, A. D., 1914.

[SEAL.]

R. T. FRAZIER,

Acting Commissioner of Patents.
